(57) **CLAIM**

The ornamental design for supporting base, as shown and described.

DESCRIPTION

FIG. 1 is a perspective view of a supporting base showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is the perspective view embodying the utilization of supporting base in which the broken line is for illustrative purposes only and forms no part of the claimed design.
